CLAIM

The ornamental design for a lamp, as shown and described.

DESCRIPTION

FIG. 1 is a perspective view of the design for a lamp as seen from the front, top;

FIG. 2 is a front elevational view thereof;

FIG. 3 is a top view thereof;

FIG. 4 is a left side elevational view thereof;

FIG. 5 is a right side elevational view thereof; and,

FIG. 6 is a bottom view thereof.

The broken line disclosure is for environmental purposes only and does not form a part of the claimed design.
